UNITED STATES PATENT OFFICE.

ELMER C. LONG, OF QUINCY, ILLINOIS, ASSIGNOR, BY MESNE ASSIGNMENTS, TO SECURITY TRUST COMPANY, OF DETROIT, MICHIGAN, A CORPORATION OF MICHIGAN.

PISTON.

Application filed April 22, 1920. Serial No. 375,673.

The main object of this invention is to provide an improved piston for internal combustion motors, whereby a better working relation is established between the piston 5 and its cylinder during the operation of the motor under highly heated conditions.

Another object of the invention is to provide a piston with entirely separated peripheral portions, and an improved way of supporting said separated portions from the opposite side of the piston.

A further object of the invention is in providing co-operating means in connection with the separated peripheral portions of 15 the piston for preventing the peripheral portions from too great a separation relative to each other, as well as means tending to prevent the peripheral portions from crowding each other.

20 Other and further objects will appear in the specification and be specifically pointed out in the appended claims, reference being had to the accompanying drawings exemplifying the invention, and in which,

25 Figure 1 is an elevation of this improved piston disclosing the side thereof bearing the entirely separated peripheral portions.

Figure 2 is an elevation of the wrist pin side of a piston.

30 Figure 3 is a vertical section taken on the line III—III of Fig. 1.

Figure 4 is a vertical section taken approximately on the line IV—IV of Fig. 3.

35 Figure 5 is a horizontal section taken on the line V—V of Fig. 3.

Figure 6 is a horizontal section taken on the line VI—VI of Fig. 3.

In the drawings, 1 designates the solid 40 end portion of the piston which is smaller in diameter than the skirt portion 2 thereof, said solid end portion 1 bearing the usual piston ring recesses 3, said solid end portion 1 and skirt portion 2 being divided by the transverse slot 4.

45 Formed on one side of the piston are a pair of adjacent separated portions 5, said portions forming part of the peripheral face of the skirt portion of the piston, and are separated therefrom by the entirely cut through longitudinally extending slots 7 which lead from the lower end 8 of the piston to the transverse slot 4, each of said portions 5 being separated from each other

by the intermediately formed inclining slot 9.

55 Formed in the skirt portion of the piston and in opposing disposition from each of the slots 7, is a longitudinally formed slot 10, said slots being cut through the thickness of the wall of the skirt portion, and in 60 which the portion disposed between each pair of slots 7 and 10 provides a wrist pin bearing side portion 11 from which a wrist pin bearing 12 interiorly extends.

65 In the manufacture of improved pistons of this character, the transverse slot 4 is entirely cut through the thickness of the wall of the skirt portion of the piston, but inasmuch as it is essential to leave the wrist pin bearing sides 11 of the piston in integral 70 relation with the solid end 1, an enlarged or bossed portion 13 is formed on the inner wall of the piston extending across the width of each wrist pin side 11.

75 That portion of the skirt of the piston arranged between the pair of slots 10, hereinafter designated as 14, and which is in opposing disposition from the separated portions 5 and adapted to support them, is integrally held from the solid end 1 of the 80 piston, and in order to overcome the weakness that might be provided by the cutting of the transverse slot 4, a transversely arranged boss portion 15 is formed on the inner wall of the piston.

85 Formed integral with the portion 14 and extending therefrom across the axis of the wrist pin bearings 12 are a pair of spaced apart bridging or connecting members 16, each of said members at their opposite ends being integrally connected with a respective separated portion 5, each of said members having an opening 17, said openings being in alignment with the wrist pin bearings 12 and are larger in diameter than the wrist pin 90 which will be supported by said bearings so that the wrist pin will not come in contact with the members 16. For reinforcing the supporting portion 14 relative to its connection with the solid end 1 of the piston, a depending rib 18 is provided which extends from the said solid end and the cross rib 19 to a position adjacent the lower end of the portion 14.

100 Horizontally supported in the members 16 adjacent the respective separated portions

5 to which they are connected is a tie bolt 20, the head 21 thereof bearing against the outer surface of one of said members 16 whereas a nut 22 is mounted on the threaded end 23 of the bolt and bears against the outer surface of the other member 16, said bolt also bearing a jam nut 24 which bears against the inner surface of the last mentioned member 16. Mounted on said bolt 20 is a coil spring 25, one end of which bears against the jam nut 24 whereas the opposite end thereof bears against one of the members 16.

From the aforementioned detailed construction of this improved piston, it is to be noted that the same is of one piece and in which the entirely separated portions 5 are hung from the opposite side of the piston wall from the portion 14. It is also to be noted that the skirt of the piston is divided into other parts than the parts 5, in which in addition to said parts or portions 5 there are a pair of depending wrist pin portions 11 and the depending portion 14.

It is a known fact that the solid end of an internal combustion engine piston is considerably smaller in diameter than the cylinder in which it reciprocates, on account of the fact that the piston rings carried by said solid end are adapted to receive the cylinder wear. In order to provide a proper balance to the piston relative to the piston rings carried thereby, as well as the piston being provided with a proper guiding and fitting relation relative to the cylinder, it therefore resides in the skirt portion of the piston to be machined of a proper size for its engagement with the cylinder. In this connection in ordinarily constructed pistons it has been found that under highly heated conditions the skirt portion of the pistons will too tightly engage the cylinder.

This invention is therefore deemed to establish a proper working fitting relation to the skirt portion of the piston relative to the cylinder under all working conditions thereof, and in which the longitudinal slot provided in the skirt of the piston will allow the portions separated by said slots to expand towards each other in a circular direction as against an outward thrusting direction upon the cylinder wall, that is, under highly heated conditions. For further enhancing the value of the several separated portions referred to of the skirt portion of the piston, the entirely cut away or wholly separated portions 5 are under control of the tie bolt 20, said bolt being adjustable, and on account of its relation with the connecting members 10 that support the respective portions 5 from the oppositely disposed portion 14, the setting of said bolt relative to the nut 22 thereof will prevent said portions 5 from separating too far relative to closing the respective slots 7, and for control-

ling said portions 5 against coming together and closing the slot 9 therebetween, the spring 25 mounted on said bolt 20 will tend to hold said portions 5 apart.

What I claim is:

1. A piston having a portion of its peripheral face entirely cut away, thereby forming a separated peripheral portion, supporting means secured to said separated portion extending to the opposite side of the piston for holding said portion in peripheral alignment with the peripheral face of the piston and means related to said separated portion for limiting the amount of separation of said portion from an adjacent peripheral portion. 70

2. A piston having a portion of its peripheral face entirely cut away, thereby forming a separated peripheral portion which extends from one end of the piston, 85 and supporting means secured to said separated portion extending to the opposite side of the piston for holding said portion in peripheral alignment with the peripheral face of the piston, said extending means being free from engagement with the wrist pin bearings of the piston. 90

3. A piston having a pair of adjacent portions of its peripheral wall entirely cut away, thereby forming separated peripheral portions, and supporting means secured to said separated portions extending to the opposite side of the piston wall for holding said portions in peripheral alignment with the peripheral face of the piston. said opposite 95 side of said piston wall being depended from the head of the piston. 100

4. A piston having a pair of portions of its peripheral face entirely cut away, thereby forming separated peripheral portions, supporting means secured to said separated portions extending to the opposite side of the piston for holding said portions in peripheral alignment with the peripheral face of the piston and means related to said separated portions for limiting the amount of separation of said portions relative to one another. 105

5. Piston having adjacent portions of its peripheral face entirely cut away, thereby forming separated peripheral portions, securing means extending to each of said portions from the interior of the piston, for holding said portions in peripheral alignment with the peripheral face of the piston, 115 said securing means being free from engagement with the wrist pin bearings of the piston. 120

6. A piston having adjacent portions of its peripheral face entirely cut away, thereby forming separated peripheral portions, securing means extending to each of said portions from the interior of the piston for holding said portions in peripheral alignment with the peripheral face of the piston, 125 130

- means tending to separate said portions from one another, and other means for limiting the amount of separation of said portions relative to one another.
5. 7. A piston closed at one end having a pair of spaced apart slots longitudinally formed in the skirt portion of the piston from the open end thereof, a pair of portions entirely cut away from the skirt portion of the piston, oppositely disposed from said slotted portion, and a rib extending from said slotted portion to each of said entirely cut away portions.
10. 8. A piston open at one end and closed at its opposite end, said piston having its skirt portion slotted entirely through the thickness of its periphery wall, and providing a pair of adjacent portions which are entirely cut away from the skirt portion, a pair of 15 wrist pin bearings disposed within the piston, and a web extending to each of said adjacent portions of said skirt portion, said webs being free from engagement with said wrist pin bearings.
20. 9. A piston having a portion of its peripheral face entirely cut away, thereby forming a separated peripheral portion, and supporting means secured to said separated portion extending to the opposite side of the piston for holding said portion in peripheral alinement with the peripheral face of the piston, and means related to said separated portion and another portion of the piston for limiting the amount of separation 25 of said portions from one another.
30. 10. A piston having a pair of portions of its peripheral face entirely cut away thereby
- forming separated peripheral portions, supporting means secured to said separated portions extending to the opposite side of the piston for holding said portions in peripheral alinement with the peripheral face of the piston, and means related to said separated portions comprising an adjustable member 40 for limiting the amount of separation of said portions from one another.
45. 11. A piston having a pair of portions of its peripheral face entirely cut away thereby forming separated peripheral portions, supporting means secured to said separated portions extending to the opposite side of the piston for holding said portions in peripheral alinement with the peripheral face of the piston, means related to said separated portions comprising an adjustable member 50 for limiting the amount of separation of said portions from one another, and resilient means mounted on said member tending to hold said portions separated.
55. 12. A piston open at one end and closed at its opposite end and having its skirt portion slotted from the open end to a point adjacent the closed end of the piston, said slotting forming adjacent disconnected portions which are wholly separated from the remaining part of the skirt portion, a pair of wrist pin bearings disposed within the piston, a web extending to each of said adjacent portions of said skirt, said webs being free from engagement with said wrist pin bearings, 60 and resilient means disposed between said webs.
65. 70
